UNITED STATES PATENT OFFICE.

FRED P. GORIN, OF SEATTLE, WASHINGTON.

LETTER-FEED-CONTROLLED REBOUND LOCK.

Application filed September 17, 1920. Serial No. 410,837.

To all whom it may concern:

Be it known that I, FRED P. GORIN, a citizen of the United States, and residing at Seattle, in the county of King and State of Washington, have invented certain new and useful Improvements in Letter-Fee-Controled Rebound Locks, of which the following is a specification.

This invention relates generally to improvements in tabulating typewriter machines, and particularly to a rebound lock mechanism for the carriage of such machines.

In controlling the rebound lock of tabulating typewriter machines, it is highly important that the return of the rebound lock to inoperative position be distinctly and positively separated, in point of time, from the instant of rebound of the carriage; that is to say, that when the carriage has moved on past the writing point against the action of its buffer spring, following the engagement of the tabulator stops, and has been returned to the writing point by the buffer spring, the rebound lock at such instant must be in operative position to prevent the carriage continuing past the writing point. Furthermore the rebound lock at such instant must remain absolutely motionless in operative position until the shock of the carriage and rebound lock impact has subsided, and the carriage moved to engage its letter feed mechanism. In rebound lock mechanisms as heretofore provided, there is constant liability of an inaccurate positioning of the carriage, incident to the operator removing his finger pressure from the tabulator key before the carriage has been fully returned to the writing point. This "dropping off" of the carriage has been heretofore provided against, as for example in Patent 1,124,219, January 5, 1915, wherein the tabulator is locked in operative position during the action of the buffer spring, and in a co-pending application filed by me July 24, 1919, Serial No. 312936, wherein the rebound lock members are frictioned against each other to prevent complete unlocking until the shock is subsided. Both of these methods are somewhat objectionable for commercial reasons, and therefore the present invention,

which obviates the necessity of either locking the tabulator in operative position, or depending upon friction, is designed to provide a construction wherein the rebound lock is caused to return to normal or unlock position directly by and as a result of the action of the typewriter letter feed mechanism.

The present invention may be generally stated as providing means for holding the rebound lock in operative position until the shock of the rebound is absorbed, and in utilizing the movement of the carriage to a position to cause cooperation of the letter feed mechanism, as is usual following a tabulating movement, to positively release the rebound lock. The construction includes cooperating elements, which positively hold the carriage out of letter feed position during the action of the buffer spring, to automatically prevent any "dropping off" of the carriage at other than the writing point.

In the drawings:—

Fig. 1 is a plan view of a portion of a tabulating typewriter machine, showing the improved mechanism applied thereto.

Fig. 2 is a rear elevation of the same.

Fig. 3 is a section on line 3—3 of Fig. 1, the cooperating parts forming the invention being shown in unlock or inoperative positions.

Fig. 4 is a similar view with the parts in locked or operative positions.

Fig. 5 is an enlarged fragmentary view in plan showing the tooth blade and connected parts in the positions occupied when the lock is in an unlocked or inoperative position.

Fig. 6 is a similar view showing the positions of the parts when the lock is in an operative position.

Fig. 7 is a similar view with the parts in the positions occupied when the buffer spring has returned the carriage to the writing point and immediately preceding the unlocking or release of the rebound lock.

Fig. 8 is an enlarged detail in plan showing particularly the mounting of the parts directly forming the rebound lock.

In the drawings 1 represents a typewriter carriage and 2 the frame structure generally. Brackets 3 are secured to the carriage and support pivot bolts 4, on which is

pivotedly supported an extension 5, carrying the usual letter feed rack 6 arranged to engage the usual pinion 7. The carriage is operated in letter feed direction by the usual tape 8, attached at one end as 9 to the carriage, and connected at the opposite end to the usual spring drum 10. An ordinary tabulator stop bar 11, notched at 12 to adjustably receive the ordinary tabulator stops 13, is slidably mounted in channel blocks 14, which are secured to set screws 15 in channels 16 in the brackets 3. The stop bar is adapted to slide freely thru the channels in the blocks 14, and by means of the adjusting screws, these blocks may be obviously so relatively adjusted as to insure the desirable free sliding action of the stop bar without binding. Bearing blocks 17 are secured to the respective ends of the stop bar, 20 and between one of said blocks and the adjacent bracket 3 is arranged the carriage buffer spring 18. The opposite block 17 carries a stop 19 adjustable therein, and adapted to abut the adjacent carriage bracket 3, 25 to act as a limit for the movement of the stop bar with respect to the carriage.

A rod 20 is secured in the bearing blocks 17 above the stop bar, as by set screws 21, and this rod is provided with a radially projecting locking strip 22 having teeth 23 in its free edge.

The usual tabulator plungers 24 are mounted in a frame carrying housing 25, and are designed to be operated in the usual manner to cooperate with the stops 13 in the tabulating operation. A bed plate 26 is removably secured upon the top of the housing 25, and has one of its ends upturned as at 27, Fig. 8. Guide plates 28 are arranged upon the bed plate, and a bit plate 29 is arranged upon the bed plate between the guide plates. The bit plate is adapted for movement transverse the bed plate, which movement between and relative to the guide plates is facilitated by ball bearings 30 between the bit plate and guide plates. The bit plate is held by a screw 31 taking into the bed plate, with the screw receiving opening in the bit plate somewhat enlarged 40 to permit the necessary movement of such bit plate. The guide plate 28 next the upturned edge 27 of the bed plate is secured by screws 33 arranged to permit a slight movement of such guide plate, under the action of adjusting screws 34 threaded thru the upturned edge 27, whereby to adjust the bearing action of the bit plate and insure a smooth even movement thereof.

A resetting plate 35 is arranged in slidable contact with the under surface of the toothed plate 22, said plates 22 and 35 being connected thru the medium of screws 36 mounted in the plate 35 projecting thru slots 37 in the toothed plate 22. The slots 37 in the plate or locking strip 22 are

formed at one end with a lateral enlargement 38 having what may be termed a cam wall 39. The enlargement 38 extends toward the teeth 23 of the locking strip, and the relative sizes of the plates 22 and 35 are such that when the screws 36 are arranged in said enlargement, as in Fig. 5, the unbroken edge of the resetting plate 35 will project slightly beyond the free ends of the teeth 23, and thereby prevent any locking cooperation with said teeth. The bit plate 29 is extended at 40 beneath the resetting plate, and is provided with one or more upstanding pins 41 on which are mounted rollers 42 to engage in a channel 43 formed in the underside of the resetting plate. The channel 43 extends longitudinally of the resetting plate and thruout the length thereof. A locking bit 44 shaped to cooperate with the teeth 23 of the locking strip is rigidly secured on the bit plate 29.

An arm 45 is secured to the feed rack 6, the free end of this arm normally lies upon the stop bar and against one edge of a block 46 secured on said bar. Resetting arms 47 project from the resetting plate 35 with their free terminals in the path of push bars 48 secured to the feed rack 6.

In a tabulating operation the feed rack 6 is raised from cooperation with the pinion 7, as is usual when a tabulator key is operated, and the arm 45 is, as a result of this movement, lifted from engagement from the block 46, and the carriage moved in the letter feed direction. When the projected tabulator plunger 24 engages the stop 13, the movement of the stop bar 11 is of course suddenly arrested at the desired writing point. The carriage however, under its inertia moves onward beyond the writing point against the action of the buffer spring 18. The carriage in this further travel carries with it the resetting plate 35, as the latter is connected to the carriage thru an arm 49 secured to one of the brackets 3 and seating in a notch 50 in the edge of said resetting plate. As the resetting plate moves with the carriage beyond the writing point, the pins 36 ride out of the enlargements 38 of the slot 37. In the initial movement of these pins, their travel, and consequently the travel of the resetting plate is transverse the locking strip 22, to thereby withdraw the free edge of the resetting plate from blocking cooperation with the teeth 23 of the locking strip 22. This movement of the pins is caused by the cam edge 39 of the slot enlargement 38. In this initial lateral movement of the resetting plate, the bit plate is moved toward the locking strip, owing to the connection of the roller 42 in the slot 43 of said resetting plate, and the bit 44 is forced into the proper tooth 23 of the locking strip, to lock the parts. Of course this locking

action takes place exactly at the writing point as determined by the tabulator stop. The carriage however continues, beyond such point against the tension of the spring 18, the movement of the resetting plate being permitted thru the free movement of the pins 36 in the slots 37. At the limit of compression action on the buffer spring, the relative parts will be substantially in the positions indicated in Fig. 6 of the drawings. The carriage now starts to return toward the writing point under the action of the buffer spring 18, moving the resetting plate toward the enlargement 38 of the slot, until at the writing point the pins 36 will engage the end walls of the slots defining such enlargement. This contact absorbs the slight impact shock of the rebound and arrests the carriage against farther travel beyond the writing point. This impact or shock is rendered very slight because the return movement of the carriage under the influence of the buffer spring 18 is accomplished against the balancing influence of the spring drum 10, which can of course be tensioned, so as to just permit the full return of the carriage to the writing point during an average run of the carriage, the rebound lock acting to prevent rebound in case of unusually long runs of the carriage. During the movement described, the arm 45 has been riding on the upper surface of the block 46, and hence the carriage cannot return to a position to permit the feed rack 6 to engage the pinion 7, until such arm 45 rides past the edge of the block, which occurs obviously at the writing point at which the carriage has been arrested by contact of the pins 36 with the walls of the slot. Furthermore in the movement of the carriage described in lifting the feed rack 6 from the pinion 7, the upper ends of the bars 48 are moved outwardly from the ends of the resetting arms 47. These arms 47 are moved outwardly toward the push bars 48 in the lateral movement of the resetting plate when the pins 36 ride out of the enlargements 38 of the slots 37 for the initial locking operation. When the carriage is completely arrested at the writing point, in the manner and thru the mechanism described, pins 36 of the resetting plate will be in line with the enlargements 38 of the slots 37 of the locking strip, but at the ends of the slots proper rather than in enlargements, that is in the positions shown in Fig. 7. As the arm 45 rides off the block 46, the feed rack 6 will move toward a cooperative engagement with the pinion 7, and in this movement the push bars 48 will engage the ends of the resetting bars 47 and move the resetting plate to its normal position, the pins 36 moving into the enlargements 38 of the slots 37. This movement of the resetting plate moves

the bit plate to its normal position thru the connection 42, thus forcing the bit 44 from the teeth 23 of the locking strip, and freeing the rebound lock.

From the above description it will be apparent that the rebound lock is caused to return to its normal position as and by the co-action of the typewriter letter feed mechanism, as unless such letter feed is returned to normal position, the rebound lock is not released. Furthermore as the arm 45 rides upon the surface of the block 46 during the action of the rebound lock mechanism, it is apparent that the typewriter feed rack is automatically held out of engagement with its feed pinion until the parts are in positions described, that is the carriage completely arrested at the proper writing point. As a result of this a "dropping off" of the carriage is absolutely prevented, except at the proper instant of cooperation, and hence any premature removal of the finger pressure on the tabulator key, or a weak or slow acting buffer spring can in no wise affect a proper operation of the rebound lock mechanism.

While the invention herein illustrated and described is shown in connection with a typewriting machine having tabulating mechanism, it is to be understood that the invention within the scope outlined by the claims is designed and contemplated for application to any tabulating mechanism, and that the application herein to the typewriter is merely illustrative of the use of the invention with tabulating mechanism.

What I claim is:

1. A typewriting machine having tabulating mechanism, a carriage buffer, a rebound lock, and means operative through the re-engagement of the carriage letter feed to release the rebound lock.

2. A typewriting machine having tabulating mechanism, a carriage buffer, a rebound lock automatically set in a tabulating operation, and means operated by the movement of the carriage letter feed mechanism toward re-engagement following a tabulating operation to release the rebound lock.

3. A typewriting machine having tabulating mechanism, a carriage buffer, a rebound lock, and means operated by the re-engagement of the carriage letter feed mechanism following a tabulating operation to release and hold out the rebound lock.

4. In a typewriting machine, tabulating mechanism, a rebound lock automatically set at the writing point as determined by such tabulating mechanism, means controlled by the re-engagement of the letter feed for releasing said rebound lock, and means for preventing such re-engagement of the letter feed until the carriage movement is arrested.

5. A typewriting machine having tabu-

- lating mechanism, a rebound lock for the carriage automatically set thru movement of the carriage beyond the writing point determined by the tabulating operation, and means actuated thru the return of the carriage letter feed to normal position following a complete arresting of the carriage movement for directly actuating the rebound lock to release the carriage.
6. The combination with a typewriting machine, of tabulating mechanism, a carriage buffer, a rebound lock, and means directly operated by the return of the typewriter letter feed to a re-engaged position for releasing the rebound lock.
7. The combination with a typewriting machine, of tabulating mechanism, including stops which collide to arrest the carriage, a buffer to absorb the shock of such arrest, a rebound lock actuated in such tabulating movement to predetermine the final position of the carriage, and means to engage and release said rebound lock following the movement of the carriage to such final position, said means being operated by the return of the typewriter feed mechanism to re-engaged position.
8. The combination with a typewriting machine, of tabulating mechanism, including stops which collide to arrest the carriage, a buffer which absorbs the shock incident to such arrest, a rebound lock, and connections between the lock and carriage which causes the lock to assume operative position at the instant of such arrest and to remain in such position until after the carriage is entirely free of all movement following the tabulating operation.
9. The combination with a typewriting machine of tabulator mechanism including stops which collide with each other to arrest the carriage, a buffer which absorbs the shock incident to such arrest, a rebound lock and connections between the same and the carriage which causes the lock to become operative when the carriage is arrested, and connections between the typewriter letter feed and the lock which causes the lock to become inoperative in the return of the typewriter letter feed parts to normal position.
10. The combination with a typewriting machine including a movable carriage and motor mechanism, of tabulator mechanism including stops which collide with each other to arrest the carriage, a buffer which absorbs the shock of such arrest, a rebound lock and connections between the same and the carriage which causes the lock to become operative when the carriage is arrested during a tabulator operation, a member for operating the lock to release the same, and means operated by the typewriter letter feed in its return to normal position to actuate said member.
11. The combination with a typewriting machine including a frame, a carriage movable thereon, motor mechanism for the carriage and step by step letter feed, of tabulating mechanism including stops on the frame and the carriage respectively which collide with each other to arrest the carriage, a buffer which absorbs the shock of such arrest, a rebound lock and connections between the same and the carriage which causes the lock to become operative when the carriage is so arrested, a member moved in the operative movement of the lock to a position to be actuated by the typewriter letter feed in its return to normal position, and means carried by said typewriter letter feed to operate said member.
12. The combination with a typewriting machine including a frame, a carriage movable thereon, motor mechanism for the carriage and step by step letter feed, of tabulating mechanism including stops on the frame and the carriage respectively which collide with each other to arrest the carriage, a buffer which absorbs the shock of such arrest, a rebound lock and connections between the same and the carriage which causes the lock to become operative when the carriage is so arrested, and connections between the lock and the typewriter letter feed which causes the release of the lock when the typewriter letter feed returns to normal position.
13. The combination with a typewriting machine of tabulating mechanism including stops, of a carriage buffer, and means which renders the typewriter letter feed inoperative during the action of the buffer, the tabulating mechanism being meanwhile free to return to normal position.
14. The combination with a typewriting machine having a typewriter feed of tabulator mechanism including stops, of a carriage buffer, and means which renders the typewriter feed automatically inoperative during the entire action of the buffer, the tabulating mechanism being free meanwhile to return to normal position, the last mentioned means including a co-operating block and arm upon the stop rod and the typewriter feed respectively.
15. The combination with a typewriting machine of tabulator mechanism, a stop bar yieldingly mounted upon the typewriter carriage, a stop on the stop bar, a stop on the frame, carriage brackets having channels, journal bearings adjustably fitted within the channels and adapted to slidably receive the said yielding stop bar.
16. The combination with a typewriting machine and feeding mechanism, of tabulating mechanism including stops to arrest the movement of the carriage, a rebound lock, and means operative by the disengagement and engagement of the feed mecha-

nism to permit operation of the rebound lock and to release said lock.

17. The combination with a typewriting machine of tabulating mechanism, a carriage buffer, a rebound lock, and means operated by the movement of the typewriter letter feed in returning to normal operative position for unlocking the rebound lock.

18. The combination with a typewriting

machine of tabulating mechanism, a carriage 10 buffer, a rebound lock, and means operated by the movement of a part of the type-writer letter feed in returning to normal operative position for unlocking the rebound lock.

15

In testimony whereof I affix my signature.

FRED P. GORIN.
